FIG. 2 is a bottom, front perspective view of the outdoor electrical device of FIG. 1;

FIG. 3 is a top, first side perspective view of the outdoor electrical device of FIG. 1;

FIG. 4 is a top, back perspective view of the outdoor electrical device of FIG. 1;

FIG. 5 is a top, second side perspective view of the outdoor electrical device of FIG. 1;

FIG. 6 is a front view of the outdoor electrical device of FIG. 1;

FIG. 7 is a back view of the outdoor electrical device of FIG. 1;

FIG. 8 is a side view of the second side of the outdoor electrical device of FIG. 1;

FIG. 9 is a side view of the first side of the outdoor electrical device of FIG. 1;

FIG. 10 is a top view of the outdoor electrical device of FIG. 1;

FIG. 11 is a bottom top view of the outdoor electrical device of FIG. 1;

FIG. 12 is a top, front perspective view of the outdoor electrical device of FIG. 1 in a second position;

FIG. 13 is a bottom, front perspective view of the outdoor electrical device of FIG. 12;

FIG. 14 is a front view of the outdoor electrical device of FIG. 12;

FIG. 15 is a back view of the outdoor electrical device of FIG. 12;

FIG. 16 is a side view of the second side of the outdoor electrical device of FIG. 12;

FIG. 17 is a side view of the first side of the outdoor electrical device of FIG. 12;

FIG. 18 is a top view of the outdoor electrical device of FIG. 12;

FIG. 19 is a bottom top view of the outdoor electrical device of FIG. 12;

FIG. 20 is a top, front perspective view of the outdoor electrical device of FIG. 1 in a third position;

FIG. 21 is a bottom, front perspective view of the outdoor electrical device of FIG. 20;

FIG. 22 is a front view of the outdoor electrical device of FIG. 20;

FIG. 23 is a back view of the outdoor electrical device of FIG. 20;

(Continued)

FIG. 24 is a side view of the second side of the outdoor electrical device of FIG. 20;

FIG. 25 is a side view of the first side of the outdoor electrical device of FIG. 20;

FIG. 26 is a top view of the outdoor electrical device of FIG. 20; and,

FIG. 27 is a bottom top view of the outdoor electrical device of FIG. 20.

In the drawings, the broken lines are for the purpose of illustrating portions of the outdoor electrical device that form no part of the claimed design.
